UNITED STATES PATENT OFFICE.

HENRY M. FRANZEN, OF LOS ANGELES, CALIFORNIA.

CONTROL FOR AIRCRAFT AND THE LIKE.

Application filed June 29, 1920. Serial No. 392,649.

To all whom it may concern:

Be it known that I, HENRY M. FRANZEN, a citizen of the United States, residing at Los Angeles, in the county of Los Angeles and State of California, have invented new and useful Improvements in Controls for Aircraft and the like, of which the following is a specification.

This invention relates to an air craft and particularly pertains to the steering and propulsion thereof.

It is the object of this invention to provide a construction in an air craft for facilitating control thereof, and to provide means whereby the craft may be caused to hover or stop in mid air and to move vertically at will so as to enable starting and landing in restricted areas.

Another object is to provide a means for drawing a volume of air from one side of a sustaining element of an air craft to create a suction adjacent the forward surface of said element, and for ejecting the volume of air at such point and in such manner as to obtain a propulsive and steering effect.

A further object is to provide a construction of the above character which is especially applicable for use on air crafts of the buoyant type in which large gas containers are employed, but which, however, may be used on aeroplanes, submarines, or other craft designed to be sustained and propelled in a fluid medium, as air or water.

Other objects will appear hereinafter.

The preferred embodiment of the invention is illustrated in the accompanying drawings, which are merely illustrative of the manner of employing the principles involved in my invention and are not intended to set forth exact details of construction which are subject to various modifications as varying conditions may render necessary without departing from the spirit of my invention as herein set forth.

In the drawings; Figure 1 is a view in longitudinal vertical section of an air craft showing the manner of employing one embodiment of my invention;

Figure 2 is a front end view;

Figure 3 is a view in transverse vertical section as seen on the line 3—3 of Figure 1.

Figure 4 is a perspective view of the air craft shown in Figure 1.

Figures 5 and 6 are views in section; and

Figure 7 is a detail in perspective illustrating modified forms of the invention. 55

Figure 8 is a view in side elevation illustrating a propulsive element employed in carrying out my invention.

Figure 9 is a detail in section showing a 60 modified form of the air conduit terminals.

More specifically, 10 indicates the body of an air-craft of the buoyant type, to which my invention is here shown as applied; the body 10 comprising an envelope or bag for 65 containing a suitable gas, as is common in dirigible balloon construction.

In carrying out my invention, I equip the structure 10 with a series of air ducts or passages which are arranged to lead from 70 points of intake and points of discharge, located at such positions on the air-craft as occasion may require and according to the size and type of craft on which my invention is to be used. In the preferred embodiment of my invention, as shown in Figures 1 to 4 inclusive, the gas containing structure 10 is provided with a longitudinally extending air duct 11, arranged axially of the gas container and opening as 80 indicated at 12 and 13 at the front and rear ends of the gas container; the terminals of the duct 11 being flared outwardly as indicated at 14 to provide funnel-shaped inlets and outlets for facilitating the intake 85 of air at either end of the duct, and the forward terminal being inclined upwardly so as to particularly facilitate the inrush of air at the upper part of the duct and thus materially aid the air craft in its 90 ascent. Mounted in the duct 11 is one or more propellers 15 which are adapted to effect intake of air at either end of the duct and cause the air entering the duct to pass therethrough and discharge therefrom as 95 will later appear; the propellers 15 being here shown as four in number with double propellers arranged adjacent the funnel-shaped terminals of the air duct. Any suitable number and arrangement of propellers 100 may be employed as occasion may require. This central longitudinally extending duct serves with the propellers as a means for inducing a suction at either end of the structure 10 as an aid to impelling or retarding movement of the air-craft in either direction. For example, in driving the air-craft in a forward direction the propellers

105

in the air duct will be operated to cause an inrush of air from the forward end of the gas container, thereby rarefying the air immediately forward of the air-craft, so as 5 to lessen or decrease the resistance to its forward movement and at the same time effect a suction tending to draw the air-craft forwardly; the volume of air flowing through the duct and discharged at the 10 rear end of the air-craft operating on and being impinged on the surrounding atmosphere at the rear end of the air-craft to impel the latter in a forward direction. Reversal of the flow of air through the duct 15 will serve to either retard forward movement of the air-craft or to impel it lengthwise as occasion may require.

As a means for aiding upward, downward, or lateral movement of the air-craft and 20 for guiding it, cross air ducts 16 are provided, which may be one or more in number and arranged at any convenient point throughout the gas container; the air ducts 16 being here shown as inclined to the vertical and extending between the upper and lower wall portion of the gas container, with their upper and lower ends opening, as indicated at 17 and 18, on opposite sides of the longitudinal vertical center of the gas container. A pair of the cross ducts 16 is here 25 shown as arranged adjacent to each end of the gas container, with the ducts of each pair communicating with the longitudinal duct 11 and intersecting with each other. Propellers 19 are arranged in the cross ducts and 30 are preferably located adjacent to the lower ends thereof and adapted to induce a flow of air into either end of the cross ducts as occasion may require.

40 As a means for directing the flow of air through the several ducts in effecting control of the air-craft, the ducts are fitted with a suitable arrangement of dampers; a damper 20 being disposed in the longitudinal duct adjacent to the rear end thereof, dampers 21 being located at the upper ends 45 of the cross ducts, and dampers 22 being provided in the cross ducts between their lower ends and their intersection with the longitudinal duct. The various dampers 50 may be operated by any suitable connections not necessary to be here shown.

The propellers 15 and 19 may be driven and controlled from any suitable source of 55 power, but are here shown as fitted with electric motors 23 and 24, preferably mounted direct upon the propellers. The propellers in the air-ducts may be employed as the sole means for impelling and steering the 60 air-craft, but they are preferably supplemented by and employed as auxiliary to other propellers and steering means, with which an air-craft may be equipped; the aircraft in this case being here shown as 65 fitted with laterally extending air-planes

and propellers 26 adapted to co-operate with the gas container in supporting the air-craft, which air-planes and propellers are adapted to be tilted vertically to effect, or aid in effecting movement of the air-craft on a vertical plane, and the propellers being further adapted to be swung laterally to direct the air-craft from side to side. The rear or stern end of the air-craft may be provided with rudders 27 and vertical and horizontal stabilizing fins 28 and 29.

In the operation of the form of the invention previously described, a gas container is preferably provided having such lifting capacity as to render the air-craft buoyant under the load it is designed to carry, so that the air-craft will have a tendency to rise under the lifting action of the gas, but which lifting effect is such that it may be overcome by directing an upward current of air through the ducts 16, and to be augmented by directing a downward current of air through these ducts. It will now be seen that by operating the propellers 19 to create the downward flow of air through the ducts 16 with the dampers 21 and 22 open, that the air-craft may be caused to rise vertically, and that by closing the dampers with one of the intersecting ducts and directing a current of air through the other a combined lateral and vertical movement of the craft may be effected, while by operating propellers 15 longitudinal movement will be obtained. By closing the dampers 22, and operating the propellers 15 with the dampers 20 and 21 open a combined longitudinal and vertical movement may be effected. The various propellers and air ducts may be operated in such combinations as to enable control of movement of the air-craft in all directions, such as raising or lowering, moving forward or backward, swinging from side to side as in turning, and tilting longitudinally, as well as maintaining the craft stationary in mid air in opposition to air currents and lift of the gas.

In some instances it may be desirable to provide a plurality of openings in the buoyant structure and connecting the air ducts therewith, such for example as shown in Figure 5, in which the buoyant structure 10 is shown as provided with a pair of spaced openings 31 and 32 at each of its ends arranged above and below the horizontal axis of the structure; the central duct 11 having branches 33 and 34 at its terminals leading to the openings 31 and 32. Dampers 35 are provided and arranged in such manner that either the duct 33 or 34 may be closed to the other, so that the air may be drawn in or discharged from either or both of the openings 31 and 32. In like manner the cross duct 16 is provided with branches 35 and 36 at its ends leading to spaced openings 37 and 38 on the upper and lower portions of 130

the structure and opening towards the front and rear ends thereof. Various other arrangements of the openings and the communicating ducts may be employed as occasion may require.

If desired the longitudinal air duct may be arranged to extend along the underside or bottom of the structure 10 as indicated at 39 in Figure 6, instead of being disposed axially of the structure, and the duct provided with an opening 40 at any suitable point for the admission or discharge of air intermediate its ends. A cross conduit 41 may extend upwardly through the structure.

13 In some instances it may be desirable to form the air duct exteriorly of the structure, such for example as shown in Figure 7, in which the longitudinal duct 42 and the vertical duct 43 are shown as mounted on 20 the outer surface of the structure.

As the steering action of the volume of air entering into or discharged from a duct is dependent upon the direction in which the air enters or is discharged; the terminals of 25 the ducts may be extended beyond the outer wall 44 of the structure, as shown in Figure 9, and the extended portions of the duct formed with accordion folds 45 or otherwise rendered flexible, so that the mouth of the 30 duct may be turned in various directions as indicated in dotted lines 46.

Any suitable form of propeller may be employed for creating a flow of air through the ducts, but the spiral propeller of the type shown in Figure 8 is preferably used; this propeller embodying a spiral blade 47 of suitable configuration mounted on a shaft 48 adapted to be driven by a motor 49 arranged intermediate the end of the propeller and around which the propeller blades turn; the motor being carried on a suitable support 50 arranged within the duct.

From the foregoing it will be seen that a volume of air may be drawn from adjacent 45 a portion of the surface of the dirigible structure and discharged at a definite point through a confined passage, and that various points of intake and discharge may be selected so as to effect movement or retardation of movement of the craft in any direction according to the will of the operator.

While I have shown and described the invention as applied to an air-craft of a buoyant or dirigible balloon type, I do not desire

to limit myself to such use as the invention 55 is equally suitable to other craft adapted to be supported and navigated in a fluid medium, such as air-planes, ships, submarines, and the like.

By arranging the rudders so that the induced current of air discharged from the rear end of the tube 11 will be directed thereagainst, a stabilizing and steering effect may be obtained independent of movement of the craft, as the induced air current impinging on the rudders will act on the craft when it is stationary in a manner substantially similar to the relative air currents caused by movement of the craft. This arrangement permits the craft being turned 70 around within a comparatively small space.

Among the advantages derived by the use of my invention is that greater lifting power and speed may be obtained and greater safety assured than by ordinary constructions.

I claim:

1. In an air-craft, a gas container having an air duct opening at one end thru the wall of the container and leading to and opening 80 thru the rear end thereof, means for inducing a current of air thru said duct, a plurality of stabilizing fins on the rear portion of said container adjacent the duct opening, and a rudder attached to each of said stabilizing fins projecting into the current of air passing thru said duct.

2. In an air-craft, a gas container having an opening at the front and rear ends thereof, an air duct extending between said openings, means for directing a current of air through said duct whereby a volume of air may be drawn from adjacent either end of the container and discharged at the other end thereof, stabilizing fins located at the rear 95 end of the duct for stabilizing the air-craft and rudders attached to said stabilizing fins so arranged that the induced current of air discharged from said rear end will be directed against the rudders.

3. In an air-craft, a gas container having an air duct opening at its ends thru the wall of the container, means for inducing a current of air thru said duct, a plurality of stabilizing fins adjacent to each of said stabilizing fins projecting into the current of air passing thru said duct.

HENRY M. FRANZEN.
